(57) **CLAIM**

The ornamental design for screwdriver with LED light, as shown and described.

DESCRIPTION

FIG. 1 is a perspective view of screwdriver with LED light showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof; and

FIG. 7 is a bottom view.

FIG. 8 is a perspective view thereof, wherein the broken line showing of the bit is for purposes of environment and forms no part of the claimed design; and,

FIG. 9 is a perspective view thereof, showing the bit storage compartment in the open position, wherein the broken line showings of the bits are for purposes of environment and form no part of the claimed design.
